O. SPERLING.
GARMENT HANGER.
APPLICATION FILED JUNE 4, 1917.

Patented Nov. 12, 1918.

UNITED STATES PATENT OFFICE.

OSCAR SPERLING, OF NEW YORK, N. Y., ASSIGNOR OF ONE-HALF TO ALFRED EMIL ANDERSEN, OF BROOKLYN, NEW YORK.

GARMENT-HANGER.

1,284,805.

Specification of Letters Patent. Patented Nov. 12, 1918.

Application filed June 4, 1917. Serial No. 172,692.

To all whom it may concern:

Be it known that I, OSCAR SPERLING, a citizen of Sweden, and a resident of the borough of Manhattan, in the county of New York and State of New York, have invented certain new and useful Improvements in Garment-Hangers, of which the following is a specification.

This invention relates to coat or garment hangers, and particularly to the types thereof that are foldable to occupy reduced space when not in use and which are extensible into operative state when utilized.

The principal object of the invention is to provide a simplified, inexpensive, conveniently operated, efficient and durable garment hanger of the kind above mentioned.

Other objects and advantages will become apparent as the specification proceeds.

With the aforesaid objects in view, the invention consists of the improvements, novel construction, arrangements and combinations of parts hereinafter described, defined in the subjoined claims, and illustrated in their preferred embodiments by the annexed drawing, wherein like elements are designated by the same reference characters throughout the several views.

In the said drawing:—

Figure 1 shows a side elevation of this improved hanger in extended condition;

Fig. 2 is a top plan view of the hanger illustrated in Fig. 1, some of the parts being shown in changed position;

Fig. 3 is a bottom plan view; and

Fig. 4 is a side view of the hanger shown folded or in a collapsed state.

In these views the hanger is shown as comprising a pair of inner sections 1, 2 hinged to each other at 3; a pair of outer sections 4, 5 that are slidable along said first named sections; a suspension member 6 and a hook 7 which are likewise hinged at 3.

The inner section 1, consists of a wire bent to form a pair of substantially horizontal members 8, the extremity of each of which is provided with a loop 9 extending outwardly and obliquely, while a central portion 10 of the wire is carried transversely and serves as a pintle for the common hinge at 3. The other inner section 2 consists of a pair of like members 11 the extremity of each of which is provided with loops 12 similar to the loops 9. The central portion

of the wire of section 2 is twisted to form 55 a pair of eyes 13, that surround the pintle 10, and it is made to extend from said eyes in the form of a loop 14 which serves as a shoulder for the section 1, when the hanger is in its open or operative state.

The outer sections 4, 5 consisting also of wire, are generally U-shaped, and made similar to each other in every respect. They include sides 15 which pass through the loops 9, 12 of the respective inner sections 1, 2 and their extremities are turned so as to form loops 16, 17 that extend inwardly and obliquely while surrounding the members 8, 11 of the respective coöperating sections 1, 2. The diagonally disposed loops 65 17 are further provided with hooks 18 for the suspension of skirts or other such garments. The diagonal location of the said hooks operates to retain the general balance 70 of the hanger when a garment is placed 75 thereupon.

The suspension member 6 consists of a wire that is twisted to form a pair of legs 19, the extremities whereof are bent into loops 20 which surround the pintle 10. The 80 upper central portion of the legs 19 is further made to form a ring 21 whereby the hanger can be suspended from a primary support. The hook 7 is made of a wire that is bent centrally upon itself at the outer extremity 22 thereof, and extends from this point in double formation up to the other or inner extremities where the wire forms a double loop 23. The latter surrounds the pintle 10 and is located between the loops 20 85 of the suspension member, which are in turn disposed between the eyes 13 of the inner section 2.

From what has been hereinabove described, it is evident that the hook 7, the section 2, and the suspension member 6 are all capable of being swung about the common pintle 10 forming part of the hinge 3. Both of the inner sections 1, 2 may be swung upwardly, and in substantial parallelism with the suspension member 6, as viewed in Fig. 4 of the drawing. Downward swinging of the sections 1, 2 below the position indicated in Fig. 1, is prevented by the members 8 of the section 1, which rest upon the transverse 105 portion 14 of the section 2.

The loops 9, 12 of the inner sections 1, 2 are slidable along the sides 15, of their re-

spective coöperating outer sections 5, 4, while the loops 16, 17 of the sections 5, 4, are similarly slidable along the members 8, 11 of the respective inner sections 1, 2. All 5 of the said loops serve as guides for the sections during their relative extension and collapsing.

When the hanger is in an operative state, Fig. 1, the suspension member 6 is disposed 10 vertically as shown, the hook 7 hanging in position to support any article placed thereon. The inner section 1 rests upon the portion 14 of the section 2, and the outer sections 4, 5 are extended to the outermost limit 15 and have their loops 16, 17 interlocking with the loops 9, 12 of the respective sections 2, 1, whereby the coöperating sections 4, 2 and 1, 5 constitute the supporting shoulder portions 20 for a coat or like garment.

20 To place the hanger in folded inoperative state, the suspension member 6 and the hook 7 are first disposed longitudinally in the position shown in Fig. 2. Next the outer sections 4, 5 are slid inwardly as in Fig. 3, 25 along the inner sections 2, 1, toward the pintle portion 10, and then the telescoped sections 1, 5 with the suspension member 6 and the telescoped sections 2, 4 with the hook 7 are swung about the hinge 3 and 30 thereby folded into the compact state shown in Fig. 4.

The straight portions of the members 8, 11 of the inner sections 1, 2 are made 35 resilient and tend to maintain parallelism, so that upon extending the outer sections 5, 4 the coacting loops 9, 16, 17 and 12, 16, 17 spread the said straight portions slightly apart from each other and firmly interlock the sections thereby retaining them in effective 40 operative condition. When the outer sections are telescoped over the inner ones, the looped portions of the latter move one toward the other upon the rounded portions of the said outer sections and thereby cause 45 a gripping action which prevents them from shifting freely outward.

While a certain preferred embodiment of this device has been shown and described, it will be understood that changes in the form, 50 arrangements, sizes and proportions and details thereof may be made without departing

from the scope of the invention as defined by the appended claims.

Having described my invention what I desire to secure by Letters Patent and claim 55 is:—

1. A foldable garment hanger made of wire, comprising a pair of interior members with closed inner ends lapping one over the other, the wire in one member running continuously across the hanger to form a hinge-pintle therefor, the wire in the other member likewise extending continuously across the hanger to constitute a rest for the closed end of the first mentioned member, the second member including eyes encircling said hinge-pintle, suspending means engaging the latter between said eyes finding a support on said rest when folded, and a pair of exterior members slidable along the sides 70 of the first pair of members.

2. A foldable garment hanger composed of wire, comprising interior members with closed inner ends extending one past the other, the wire in one member running continuously across the center of the hanger to constitute a pintle therefor and the wire in the other member being looped around said pintle and made to reach across the hanger in a continuous manner parallel with the 75 pintle to provide a supporting ledge for the closed end of the first named member, the outer ends of the members being open and each provided with eyes on opposite sides thereof, exterior members arranged to slide 80 through said eyes and having similar eyes adapted to slidably engage the sides of the interior members, hooks forming continuations of two of the last mentioned eyes and diagonally located with relation to the hanger one on each side of the same, said hooks being both turned inward and directed toward each other on opposite sides of the 85 pintle when the hanger is folded, and suspending means engaging the pintle.

Signed at the borough of Manhattan, in the county of New York and State of New York, this 2nd day of June, A. D. 1917.

OSCAR SPERLING.
